JAMES HOWARD AND E. TENNEY BOUSFIELD, OF BEDFORD, ENGLAND.

Letters Patent No. 66,590. dated July 9, 1867; patented in England, January 11, 1867.

IMPROVEMENT IN STEAM-GENERATORS.

The Schedule referred to in these Letters Patent and making part of the same.

TO ALL WHOM IT MAY CONCERN:

Be it known that we, JAMES HOWARD, of Bedford, in the county of Bedford, Agricultural Engineer, and EDWARD TENNEY BOUSFIELD, of the same place, Engineer, have invented "Improvements in Tubular Steam-Boilers;" and we do hereby declare that the following is a full and exact description of our said invention.

This invention relates to improvements on the tubular boiler, for which we obtained an American patent, bearing date October 23, 1866, the object being, first, to provide a more effective circulation of the water in the vertical tubes of the various sections of the boiler, and thereby to prevent or materially retard incrustation of the tubes; secondly, to provide a simple and secure water-tight joint between the transverse water tubes and the vertical tubes; thirdly, to strengthen the transverse pipes upon which the vertical tubes are set; and, fourthly, to simplify the construction of the furnace and flues. In the accompanying drawing—

Figure 1 is a plan view of the improved boiler.

Figure 2 is a transverse sectional elevation of the same; and

Figure 3 is a partial sectional elevation on an enlarged scale of a portion of one of the groups of tubes.

A A are the vertical tubes, connected together in groups at bottom by transverse pipes B B, and at top by transverse pipes C C; and the groups are connected together at bottom by short pipes D D, and at top by a longitudinal steam pipe, E. In order to quicken the circulation of the water, we insert internal tubes F, of peculiar construction, in the vertical tubes A, and use them as channels for conducting down the upper portion of the water in the boiler to the horizontal pipes, which connect with the lower ends of the vertical tubes, and constitute, with a given length of the tubes A, the water space of the boiler. These inner tubes we fix in a concentric position in the main vertical tubes, and cause them to rest on the bottom of the horizontal tubes, as shown best at fig. 3. The internal tubes F we make long enough to reach to the highest water level of the boiler, and their upper ends, which are open, we slit, as shown at fig. 2, or pierce laterally to a distance a little below the lowest water level of the boiler. The lower ends of the tubes F we form so that the water will have a free passage out at the bottom of the tubes. The effect of this arrangement will be to create a downward current of the water at or near the water level, (notwithstanding the variation in that level,) through the internal tubes, as indicated by the arrows in fig. 3, and a consequently increased upward current outside those tubes. The deposit, therefore, while the boiler is in action, of earthy and saline particles contained in the water, and the consequent incrustation of the boiler, will be greatly retarded, if not entirely prevented. In order to insure tightness in the bottom joints of the vertical tubes, we form the annular recesses of the lower transverse pipes in which the vertical tubes are seated of a tapered or V section, or with one of the sides of the recess inclined, as shown at a a, fig. 3. The holding bolts will then, as they are screwed tight, draw down the tubes into a contracted space, and cause close contact between the abutting surfaces. The like result may be obtained by tapering the end of the tubes, and making the annular recesses square in cross-section, and of somewhat less width than the full thickness of the tube, as shown at b b in the same figure. In order to strengthen the transverse pipes B without materially adding to their weight, we cast them with internal divisions c c, through the lower part of which is a hole to allow of the free circulation of the water. Instead of encasing the boiler thus constructed, as heretofore, with independent walls of brick-work, we propose to fill the spaces between the outer tubes with fire-bricks, moulded to suit the shape of the spaces to be filled in, as shown at d d, fig. 1. We are thus enabled, by the use of a minimum of material, to form the furnace walls, and at the same time to save space, thereby obtaining important advantages in the setting up of the boiler, more especially when it is adapted to marine purposes. The fire-bars may be supported by brick-work, or in any approved manner; and when the fire-place is divided, as shown in the drawing, we propose to form the dividing wall of water-tubes, filling in the spaces with fire-brick or other blocks, as when forming the outer walls. The fire and ash-pit doors will be applied in the ordinary manner, the blocks being moulded to suit the spaces to be filled between the frames of the doors and the tubes. When we wish to divide the heating-chambers horizontally, so as to return the current of heated gases, we cast collars or bands on the tubes, as shown at e e in fig. 2, which form supports for the dividing bricks or plates.

Having now set forth the nature of our invention of "improvements in tubular steam-boilers," we wish it to be understood that we are aware of inner tubes having been proposed for quickening the circulation of water in

the vertical tubes of boilers, such tubes being closed at the bottom and filled with water; but in the arrangement of these inner tubes, so far as we are aware, no provision has been made for the circulation of the water throughout the whole depth of the water space. In our arrangement, the outer tube communicates with the steam and water spaces at top and bottom, and provision is made in the internal tube for a differential water level. We do not, therefore, claim the use of inner tubes, of whatever construction, for promoting the circulation of the water; but we claim as of our invention—

1. The inner tubes F, provided with the slits near their tops, whereby the differential water level is obtained, in combination with the transverse pipes B, containing internal divisions c, as herein described, for the purpose specified.

2. Securing a water-tight joint between the tubes and transverse pipes, in the manner above described.

3. The fire-bricks d d, constructed as described, when employed to fill the spaces between the outer tubes B, as herein set forth, for the purpose specified.

In witness whereof, we, the said JAMES HOWARD and EDWARD TENNEY BOUSFIELD, have hereunto set our hands and seals, the eighteenth day of March, in the year of our Lord one thousand eight hundred and sixty-seven.

JAMES HOWARD. [L. S.]
EDWARD TENNEY BOUSFIELD. [L. S.]
